UNITED STATES PATENT OFFICE.

CARL E. RICHSON, OF BROOKLYN, NEW YORK, ASSIGNOR OF ONE-HALF
TO GUSTAF PERSON WERN, OF NEW YORK, N. Y.

SUSPENSION CABLEWAY, CARRIER, AND CARRIAGE.

SPECIFICATION forming part of Letters Patent No. 597,296, dated January 11, 1898.

Application filed March 8, 1897. Serial No. 626,445. (No model.)

To all whom it may concern:

Be it known that I, CARL E. RICHSON, of Brooklyn, in the county of Kings and State of New York, have invented a new and Improved Suspension Cableway, Carrier, and Carriage, of which the following is a full, clear, and exact description.

The invention relates to aerial hoisting and transportation devices; and its object is to provide a new and improved suspension cableway, carrier, and carriage arranged to properly support the hoisting-rope and the endless carriage-rope and to permit the carriage to automatically switch past the carriers.

15 The invention consists principally of a fixed rope carrying a series of hangers secured on the same, a main cable forming a track for the carriage and movable laterally adjacent to the hangers, the hangers being provided 20 with means to engage the cable and pulleys to support the hoisting-rope and the endless carriage-rope, and means for switching the carriage past the said hangers and returning the cable and the ropes to the hangers after 25 the carriage has passed.

The invention further consists of a carriage provided with tracks adapted to engage pulleys on the hanger to move the carriage and hanger transversely apart for the carriage to 30 pass the hanger.

The invention also consists of certain parts and details and combinations of the same, as will be fully described hereinafter and then pointed out in the claims.

35 Reference is to be had to the accompanying drawings, forming a part of this specification, in which similar characters of reference indicate corresponding parts in all the figures.

Figure 1 is a side elevation of the improvement as applied. Fig. 2 is an enlarged side elevation of the improvement. Fig. 3 is a sectional plan view of the same on the line 3 3 of Fig. 2. Fig. 4 is a similar view of the same on the line 4 4 of Fig. 2. Fig. 5 is an end elevation of one of the hangers with the cable and ropes in section, and Fig. 6 is an enlarged transverse section of the improvement on the line 6 6 of Fig. 2.

The cable A is stretched between suitable 50 towers B B' or other structures or elevated

points, and the said cable between said towers passes over pulleys C, journaled on hangers D, placed suitable distances apart and supported at their upper ends on a rope E, likewise stretched from one tower B to the other 55 tower B'. On the cable A are mounted to travel the pulleys F', journaled in the frame F² of the carriage F, connected in the usual manner with the endless rope G, passing over pulleys on the towers B B' to wind on a suitable windlass under the control of the operator, so that the carriage F can be pulled forward or backward on the cable A. The upper run of the rope G is supported between the towers B B' on pulleys C³, journaled in 60 the hangers D, and the lower run G' of the said carriage-rope G is supported on pulleys C³, likewise journaled on the hangers D, and the said run passes between sets of pulleys F⁴, journaled on the frame F² of the carriage, as 65 plainly illustrated in Fig. 2. In the frame F² of the carriage are journaled the hoisting-pulleys H, over which passes the hoisting-rope I, connected with a suitable hoisting mechanism to raise or lower the load J, supported on 70 the said hoisting-rope, as plainly indicated in Fig. 1. The hoisting-rope I is supported between the carriage and the towers by pulleys C⁴, journaled on the hangers D, as indicated in the drawings. Thus it will be seen that 75 the carriage-rope G and the hoisting-rope I are suitably supported at intervals on the hangers D, so that none of the ropes is slack.

Now in order to allow the carriage F to pass each of the hangers D as the carriage moves 85 forward or backward over its cable A, I provide the following device: On the carriage-frame F² and near the upper portion thereof is arranged a track K, formed with the fixed track-section K' and the end sections K² and 90 K³, pivotally connected with the ends of the fixed section K', so as to allow the said end sections to swing up and down. The middle or fixed section K' extends on one side of the frame F², and the end sections K² and K³ are 95 curved transversely to extend over to the other side of the cable, as plainly indicated in Fig. 3, and on the outer ends of the said sections K² and K³ are journaled horizontally-disposed pulleys K⁴ and K⁵, respectively, 100

traveling on the cable A. Springs K⁶, secured on the carriage-frame F², press with their free ends on the hinged end sections K² or K³, so as to hold the pulleys K⁴ and K⁵ in engagement with the cable A. A similar track L is arranged in the lower part of the frame F² and is provided with a fixed section L¹, and the hinged end sections L² and L³ are curved transversely and formed at their ends with shoes L⁴ and L⁵, respectively, for the passage of the carriage-rope G. On each of the hangers D is fulcrumed at N' a transversely-extending lever N, carrying at its free end a wheel N², extending a suitable distance from the inner face of the support to engage the track K at either end section K² or K³, according to the direction in which the carriage is traveling. Now as this wheel N² travels along the curved end section K² or K³ on the forward movement of the carriage it is evident that the carriage and the corresponding support D are moved laterally apart, so that the cable and the ropes G and I are lifted off their pulleys C², C³, and C⁴ to permit the carriage to pass the hanger. The lever N is normally in the position shown in Fig. 5, and is held therein by a spring N³, so that the curved outer end N⁴ of the said lever extends close to the top of the pulley C and the foot C' to prevent the cable A from lifting the said pulley unless the lever N is swung upward into the position shown in Fig. 6, the upward movement of the lever being accomplished by the wheel N², traveling over the corresponding end sections K² or K³ of the track K. The lower track L is engaged at either end L² or L³ by the pulley C⁴, as shown in Fig. 6, so that the hanger and the carriage are well separated one from the other, and the cable A and ropes G and I are taken off from their pulleys C, C², C³, and C⁴ and carried in alinement with the carriage, as will be readily understood by reference to Figs. 3 and 4. In order to hold the ropes G and I firmly in place on the pulleys C², C³, and C⁴ during the time the carriage is between the two adjacent hangers D, I provide suitable locking devices, controlled from the lever N and consisting of a link O, pivotally connected with the said lever N and provided with hooks or U-shaped arms P, P', and P'', fulcrumed on the hanger D and adapted to extend around the ropes, so as to prevent the same from accidentally leaving the pulleys, as indicated in Fig. 5. It is understood that the lever N is then in a lowermost position by the action of the spring N³, so as to lock the cable A in place between the pulley C and the foot-piece C'; but when the carriage nears a hanger and the wheel N² passes into the mouth of the end track-section K² or K³ and travels up and along the same an upward-swinging motion is given to the lever N, whereby the link O pulls on the hooks P P' P'' to swing the same downward into the position shown in Fig. 6 to permit the ropes to leave the said pulleys C² C³ C⁴, so

as to allow the carriage to switch past the hanger. As soon as the wheel N² and the pulley C⁴ have left the tracks K and L the cable A and the ropes G and I pass back upon their pulleys on the hanger just passed by the carriage, and the lever N is drawn back to its lowermost position by the action of the spring N³, so as to close the hooks P P' P'' and again lock the ropes in place on their pulleys. At the same time the lever N itself locks the cable A in position between the pulley C and the foot-piece C', as shown in Fig. 5.

Having thus fully described my invention, I claim as new and desire to secure by Letters Patent—

1. The combination of the fixed rope or support, the hangers carried thereby, the cable or track arranged to engage the hangers and movable laterally in relation thereto, and a carriage mounted to travel on said cable and provided with parts arranged to engage the hangers and to swing the carriage with its cable away from the hangers, substantially as described.

2. The combination of the fixed rope or support, the hangers carried thereby, the cable or track arranged to engage the hangers and movable laterally in relation thereto, and a carriage mounted to travel on said cable and provided with transversely-extending guides arranged to engage the hangers and to swing the carriage with its cable away from the hangers, substantially as described.

3. The combination of the fixed rope or support, the hangers carried thereby, the cable or track normally engaging the hangers, and movable laterally in relation thereto, a holder movably connected to the hangers and normally extending exteriorly of the cable to prevent outward movement thereof, and a carriage mounted to travel on said cable and provided with parts adapted to swing the holder out of the path of the cable so as to allow the same to move laterally, the carriage also having parts adapted for engagement with the hangers to swing the carriage with its cable away from the hangers, substantially as described.

4. The combination of the fixed rope or support, the hangers carried thereby and provided with pulleys or other rope-supports, hooks or holders movably connected to the hangers and extending exteriorly of the rope-supports, a cable or track normally engaging some of said pulleys, yet capable of being disengaged therefrom laterally, a pulling-rope likewise running over some of the pulleys, a carriage mounted to travel on said cable and connected to the pulling-rope, means for throwing the holders or hooks out of the path of the cable and rope when the carriage is at one of the hangers, and means for swinging the carriage and its cable away from the hangers when passing the same, substantially as described.

5. A device of the class described provided with a carriage supporting a switch-track

made in sections, of which one is fixed and the end sections are hinged, substantially as shown and described.

6. A device of the class described provided with a carriage-cable, and a carriage mounted to travel thereon, and provided with a switch-track made in sections, of which one is fixed on the carriage, and the other sections are hinged on the fixed section and extend transversely to the said cable, substantially as shown and described.

7. A device of the class described provided with a carriage-cable, a carriage mounted to travel thereon, and provided with a switch-track made in sections, of which one is fixed on the carriage, and the other sections are hinged on the fixed section and extend transversely to the said cable, and a pulley on the free end of each hinged section and engaging the said cable, as set forth.

8. A device of the class described provided with a carriage mounted to travel, a pulling-rope for the said carriage, and a track supported on the carriage and provided with a fixed track-section and hinged end sections, each formed at its free end with a shoe engaging the said pulling-rope, substantially as shown and described.

9. The combination of the fixed rope or support, a series of hangers secured thereto, a carriage, a pulling-rope therefor, a hoisting-rope, a main cable forming a track for the carriage and movable laterally adjacent to the hangers, the latter being provided with means for engaging the cable and pulleys to support the hoisting-rope and the pulling-rope, and means for switching the carriage

past the said hangers and for returning the cable and the ropes to the hangers after the carriage has passed, substantially as described.

10. A device of the class described, comprising a hanger carrying a series of pulleys to be engaged by cables and ropes, a spring-pressed lever fulcrumed in the said hanger and adapted to receive motion from the carriage traveling over the said cable, and hooks pivotally connected with the said lever and adapted to lock the ropes in place on the said pulleys, substantially as shown and described.

11. A device of the class described comprising a carriage having an upper and lower track located respectively adjacent to the cable or other support on which the carriage travels and to the pulling-rope by which motion is imparted to the carriage, and a hanger-carrying means for engaging the said tracks to separate the carriage and hanger, substantially as shown and described.

12. In a device of the class described, the combination with a carriage mounted to travel on a cable and adapted to be moved by a pulling-rope, and supporting hoisting-pulleys and a hoisting-rope, a hanger provided with pulleys for supporting the said cable and ropes, tracks carried by the said carriage, means carried by the said hangers for engaging the said tracks, and devices for locking the cable and ropes in place on the pulleys, as set forth.
